UNITED STATES PATENT OFFICE.

FREDERICK BIRL GLENN, OF LYNCHBURG, VIRGINIA, ASSIGNOR OF ONE-HALF TO JAMES H. GUTHRIE, OF LYNCHBURG, VIRGINIA.

ADDING-MACHINE.

No. 866,355.

Specification of Letters Patent.

Patented Sept. 17, 1907.

Application filed December 27, 1906. Serial No. 349,690.

To all whom it may concern:

Be it known that I, FREDERICK BIRL GLENN, a citizen of the United States, residing at Lynchburg, in the county of Campbell and State of Virginia, have invented a new and useful Adding-Machine, of which the following is a specification.

This invention relates particularly to means for adding numbers.

The principal object is to provide novel means of an exceedingly simple nature, whereby this operation can be mechanically performed without the necessity of any involved mental calculations.

The preferred form of construction is illustrated in the accompanying drawings, wherein:

Figure 1 is a plan view of the mechanism, with a portion of the top of the casing and with the register broken away. Fig. 2 is a cross sectional view through the structure. Fig. 3 is a vertical longitudinal sectional view therethrough. Fig. 4 is a top plan view of the register, with the top of the casing removed.

Similar reference numerals designate corresponding parts in all the figures of the drawings.

In the embodiment illustrated, a frame casing 5 is employed that may be of any suitable shape, and is preferably supported by end standards 6. Upon the top 7 of this casing is mounted a register disposed at an inclination and supported on legs 8 fastened to said top.

The register consists of a casing 9, within which are disposed a plurality of rotatable number wheels 10 and 11, two being shown, though any number can be employed, as will be evident to those skilled in the art. One of the wheels 10, is provided with a consecutive series of numbers from zero to nine, the other 11, having a series from zero to twenty-nine. The wheel 10 is provided with a peripheral series of ratchet teeth 12, with which a spring-pressed dog 13 cooperates, said dog permitting the rotation of the wheel in one direction, but preventing its retrograde movement. The wheel 11 is also provided with a series of ratchet teeth 14, and 40 a spring-pressed dog 15 co-operates therewith. The wheel 10 furthermore, has a projecting tooth 16 that is arranged to engage the teeth 14 of the wheel 11, and effect a movement of said wheel upon each rotation of the wheel 10. The numbers on the wheels 10 and 11 are respectively visible through eight openings 17 and 18, in the top of the casing, the opening 18 being in the form of an offset from a circular opening 19, in which is located a knob 20, by means of which the wheel 11 may be manually operated.

Secured at its upper end to the wheel 10, is a rotatable shaft 21 that extends downwardly at an inclination beneath the register and through the top 7 of the machine casing. A disk or wheel 22 is fixed to the

lower end of the rotatable shaft, and has a peripheral series of notches 23, forming teeth 24 between them. 55

A pinion 25 is journaled upon the lower portion of the shaft 21 and is supported thereon by the disk or toothed wheel 22. A spring pressed dog 26, mounted on the disk or toothed wheel 22, is arranged to engage the pinion 25, and thus it will be evident that if the pinion 25 is rotated in one direction, the dog, interlocking with the teeth of said pinion, will cause the rotation of the disk or toothed wheel 22, and consequently of the shaft 21, thereby effecting the operation of the register. The means for moving the pinion 25 is preferably constructed 60 as follows:—A rock shaft 27 is journaled within the machine casing, and is provided with a quadrant-gear 28 that meshes with the pinion 25, and is disposed above the path of movement of the dog 26. The rock shaft has an offset portion 29 that extends around the 70 rotatable shaft. A plurality of arms 30 of different lengths are carried by the rock shaft, and are normally disposed in substantially horizontal relation. A spring 31, engaging one of the arms, serves to hold the series of arms and the rock shaft in a predetermined position, 75 yet permitting the downward movement of the former.

A plurality of reciprocal number keys 32 are disposed along the front margin of the machine casing and have upright stems 33 passing downwardly therethrough, with their lower ends resting in seats 34, 80 formed in the upper sides of the free ends of the arms 30. The keys are provided with numeral designations one to nine inclusive, as shown in Fig. 1. The "one" key preferably cooperates with the longest arm, and the "nine" key with the shortest. The various key stems are preferably provided with offset feet 35, that are located at one side of the arms, as shown in Fig. 3. 85

To prevent overthrow of the register, a rock shaft 36 is journaled in the machine casing, in front of and below the rock shaft 27, and has a stop dog 37 normally disposed beneath the disk 22 and movable upwardly into the notches thereof when said notches align with the dog. This rock shaft furthermore has a plurality of arms 38, the free ends of which are disposed at different heights, and are respectively located in the paths of movement of the feet 35 of the key stems. The highest of the arms is disposed beneath the foot of the key bearing the numeral one, and the lowest is located in the path of movement of the "nine" key. 95

The operation of the structure is as follows. Assuming the register wheels arranged so that the zero designations are exposed, the keys and the gearing being properly proportioned, upon the depression of any key, the wheel 10 will be revolved a sufficient distance to expose the number of the wheel 10 corresponding to 105 the key depressed. Therefore, upon the consecutive

operation of the different keys, it will be evident that addition will be performed, and the result disclosed by the register. When a key is depressed, the quadrant-gear 28 operates upon the pinion 25 so as to cause the rotation of the dog 26, the disk 22, the shaft 21, and consequently the number wheel or wheels. When the shaft returns, under the impulse of the spring 31, the pinion 25 will rotate freely and the dog 26 will ride over the teeth thereof, while retrograde movement of the register wheel 10 will be prevented by the dog 13. Moreover, as the key nears the limit of its down-stroke, its foot will engage one of the arms 38, thereby rocking the shaft 36 and raising the dog 37 into a notch of the disk 22, preventing overthrow of the register. Upon the return of the key, the dog moves downwardly, a spring 39 being preferably employed for effecting the return movements of the rock shaft 36, the arm 38, and the dog.

From the foregoing, it is thought that the construction, operation, and many advantages of the herein described invention will be apparent to those skilled in the art, without further description, and it will be understood that various changes in the size, shape, proportion, and minor details of construction, may be resorted to without departing from the spirit or sacrificing any of the advantages of the invention.

Having thus fully described my invention, what I claim as new, and desire to secure by Letters Patent, is:—

- 30 1. In adding mechanism of the character described, the combination with a casing, of registering mechanism located upon the casing, an upwardly extending shaft connected to the registering mechanism and having its lower end within the casing, a rock shaft located longitudinally within the casing and disposed in angular relation to the upright shaft, gearing connecting the shafts and including ratchet mechanism, and numeral keys located on the casing and having stems that project into the casing and effect the operation of the rock shaft.
- 40 2. In adding mechanism of the character described, the combination with a frame casing, of a register casing located upon the top of the frame casing and having its front face disposed at an inclination, registering mechanism located in the register casing, an upwardly extending shaft having its upper end connected to the registering mechanism and having its lower end within the frame casing, a substantially horizontal rock shaft located longitudinally within the frame casing, gearing connecting the shafts and including ratchet mechanism, arms projecting from the rock shaft, and numeral keys located upon the top of the casing and having stems extending downwardly into the same and co-operating with the arms to effect the operation of the rock shaft.
- 50 3. In adding mechanism of the character described, the combination with registering mechanism, of an upwardly extending shaft connected thereto, a rock shaft disposed transversely of the upwardly extending shaft, a gear loosely journaled on said upwardly extending shaft, a segmental gear, fixed to the rock shaft and meshing with the loose gear, a support fixed to the upwardly extending shaft, a dog pivoted on the support and engaging with the gear, numeral keys, and means for transmitting motion from the numeral keys to the rock shaft.
- 60 4. In adding mechanism of the character described, the combination with registering mechanism, of an upstanding rotary shaft associated therewith, a rock shaft, a pinion journaled on the rotary shaft, a support for the pinion secured to the shaft below said pinion, a dog mounted on the upper side of the support and co-operat-

ing with the pinion, gearing connected to the rock shaft 70 and associated with the pinion, and numeral keys for effecting different movements of the rock shaft.

5. In adding mechanism of the character described, the combination with registering mechanism including co-acting number wheels, of an upwardly extending shaft 75 fixed at its upper end to the center of one of the wheels, a rock shaft disposed transversely of the lower end of the upwardly extending shaft, a segmental gear fixed to the rock shaft, a support fixed to the lower end of the upwardly extending shaft, a gear loosely journaled on said upwardly extending shaft and resting upon the support, said gear being in mesh with the segmental gear of the rock shaft, a dog carried by the support and engaging the loose gear, numeral keys, and mechanism for transmitting motion from the numeral keys to the rock shaft. 80 85

6. In adding mechanism of the character described, the combination with registering mechanism, of an upstanding rotary shaft associated therewith, a rock shaft, a pinion element journaled on the rotary shaft, a supporting element for the pinion element secured to the shaft below 90 the pinion element, said pinion element resting upon the supporting element, a dog mounted on one of the elements and co-operating with the other to prevent their relative movement in one direction and permit their relative movement in an opposite direction, gearing connected to the 95 rock shaft and associated with the pinion element, and number keys for effecting different movements of the rock shaft.

7. In adding mechanism of the character described, the combination with registering mechanism, of an upwardly 100 extending shaft connected at its upper end thereto, a toothed wheel fixed to the lower end of the shaft, a gear loosely journaled on the shaft above the toothed wheel and supported thereby, a rock shaft having a segmental gear in mesh with the loose gear, a plurality of keys having independent connections with the rock shaft, another rock shaft disposed below and substantially parallel to the first mentioned rock shaft, said latter shaft having a plurality of outstanding arms located in the path of movement of the keys and at different distances therefrom, 110 and a stop dog carried by the latter rock shaft and movable into coaction with the toothed wheel of the upwardly extending shaft.

8. In adding mechanism of the character described, the combination with registering mechanism, of a rotatable shaft connected thereto, a rock shaft, numeral keys for operating the rock shaft, gears, one of which is carried by the rock shaft, another being journaled on the rotatable shaft, a toothed wheel fixed to the rotatable shaft, a dog mounted on the wheel and co-operating with the gear that is journaled on said rock shaft, and an overthrow preventing dog movable into and out of co-operation with the toothed wheel. 115

9. In adding mechanism of the character described, the combination with registering mechanism, of a rotatable shaft connected thereto, a toothed wheel fixed to the rotatable shaft, a pinion journaled on the rotatable shaft, a dog carried by the toothed wheel and co-operating with the pinion, a rock shaft having a quadrant-gear co-operating with the pinion, a plurality of outstanding arms carried by the rock shaft, reciprocal numeral keys that engage the arms to operate the same, and thereby the rock shaft, another rock shaft having outstanding arms disposed beneath the first mentioned arms and the keys, and a stop dog carried by the second rock shaft and movable into and out of co-operation with the teeth of the wheel that is fixed to the rotatable shaft. 125 130 135

In testimony, that I, claim the foregoing as my own, I have hereto affixed my signature in the presence of two witnesses.
